SIGNAL TRANSLATING AND MODULATING SYSTEM

Harold A. Wheeler, Great Neck, N. Y., assignor
to Hazeltine Corporation, a corporation of
Delaware

Application March 27, 1935, Serial No. 13,227

21 Claims. (Cl. 250—20)

My invention relates to signal-translating and -modulating systems, and more particularly to such systems including a vacuum tube provided with a virtual cathode; that is, a secondary source of electrons controllable independently of the electron stream from the main cathode.

The invention is directed specifically to an arrangement for neutralizing, or compensating for, any regenerative or degenerative feedback effect upon a signal-translating or -amplifying control electrode of another electrode or electrodes, included in the same vacuum tube, and their connected circuits, such other electrodes usually co-operating in the formation of the virtual cathode; and for neutralizing or compensating for any remodulating or demodulating effect of the signal-translating or -amplifying control electrode and its connected circuit upon the modulating action in the same vacuum tube.

It has been proposed heretofore to utilize as a modulator of a signal-translating system, a multi-electrode vacuum tube including means for forming a "virtual cathode" or secondary source of electrons. Such a virtual cathode may be established by a pair of closely spaced electrodes, the one nearer the cathode being maintained at a positive potential with respect thereto and the other at a negative potential with respect thereto. The latter electrode is effective to retard the flow of electrons beyond the first electrode and to form a cloud or mass of slow-moving electrons having characteristics very similar to those of the actual cathode. The intensity of the virtual cathode may be controlled by an emission control electrode interposed between the virtual and actual cathodes. The electron stream from this virtual cathode may be controlled by a suitable electrode disposed between the virtual cathode and an output electrode further from the actual cathode. A signal-translating and -modulating system utilizing a vacuum tube of the type just described is disclosed and claimed in U. S. Letters Patent No. 1,958,027, granted May 8, 1934, upon my application.

The advantages of such a system are set forth in detail in that patent, among which an important one is that, when the vacuum tube is utilized in an oscillator-modulator circuit, the bias of the amplifying control electrode, or signal input electrode, may be varied, as by an automatic volume control circuit, without disturbing the characteristics of the oscillator circuit including two electrodes nearer the actual cathode, which generally constitute the grid and anode of the oscillator section of the tube.

In the system described above, there is a certain amount of unavoidable capacitive coupling between each of the several electrodes upon which is impressed a voltage and all of the other electrodes, this coupling being effective to transfer currents from any given electrode to the circuits associated with the other electrodes. These currents develop in such circuits voltages which appear on their associated electrodes, and which are dependent upon the impedances of the circuits at the frequency of the voltage impressed upon the given electrode. These induced voltages on the other electrodes of the vacuum tube modify the effect of the given electrode upon the resultant electron current flowing to the anode of the vacuum tube and its associated output circuit. The effect of these induced voltages may be either aiding or opposing, depending upon whether the circuits in which they appear are inductively or capacitively reactive at the frequency in question.

The capacitive couplings between the several electrodes in a multi-electrode vacuum tube of the type described above, provided with a virtual cathode, is made up of two components, the first being the usual geometrical capacitance, which is dependent primarily upon the physical relationship of the electrodes within the vacuum tube. The second component, which is peculiar to this type of vacuum tube including a virtual cathode, may be termed a "space-charge coupling" and is due to variations or fluctuations in the space charge of the mass or cloud of electrons constituting the virtual cathode and positioned between the virtual-cathode-forming electrodes. It will be understood that variations in the space charge capacitively induce displacement currents in the circuits of any electrodes subject to the electrostatic field of the space charge.

However, as between certain of the electrodes of a multi-electrode vacuum tube, the capacitive coupling is negligible, either because they are relatively remote or because of their electrostatic isolation by means of an interposed auxiliary screen electrode; for example, a screen adjacent the anode, which anode would otherwise produce the most noticeable disturbing effect upon the signal amplification control or emission control electrodes because of the relatively high voltage at which the anode operates. Further, the circuits associated with certain of the electrodes are usually tuned to widely different frequencies so that the impedances of certain of the circuits are low at the frequency of the voltage impressed

upon a given electrode, so that the voltage developed across such circuits is negligible.

In particular, there exists an undesirable capacitive coupling, comprising mainly geometric 5 capacitance such as described above, between the signal input or amplification control electrode and the electrode which cooperates therewith to form a virtual cathode and which usually constitutes also the anode of the oscillator section 10 of the vacuum tube. This relatively high capacitive coupling is due particularly to the relatively close spacing of these two electrodes. This coupling results in two effects which may modify the overall conversion gain of the system.

15 In the first place, the trans-conductance between the signal input electrode and the adjacent electrode nearer the cathode, which may constitute the oscillator anode, produces a variation in the current in the circuit of this latter electrode 20 and develops upon the electrode a voltage of signal input frequency dependent in phase and magnitude upon the impedance of this circuit. This voltage, in turn, capacitively induces a current in the signal input circuit which develops 25 upon the signal input electrode a voltage dependent in phase and magnitude upon the impedance of the signal input circuit and which may either aid or oppose the impressed signal input voltage. Since the trans-conductance between 30 these electrodes is negative as compared with an ordinary triode, an inductive impedance in the oscillator anode circuit with respect to the signal frequency produces an effect which opposes that of the impressed signal input voltage; that is, effectively reduces this voltage. This result is the usual one in systems in which the oscillator frequency is higher than the signal frequency and the oscillation circuit is inductive 35 at the signal frequency. This effect may be 40 termed, broadly, regeneration and may be positive or negative (degeneration) dependent upon whether it increases or decreases, respectively, the signal input voltage. Although this regeneration does not directly affect the conversion gain 45 of the tube, its effect on the signal input voltage results in a change in the overall conversion gain of the system.

The capacitive coupling between the signal input electrode and the adjacent electrode nearer the cathode, that is, the oscillator anode, similarly 50 gives rise to a voltage of the oscillator frequency on the signal input grid which may aid or oppose the action of the emission control electrode. This effect may be termed, broadly, 55 modulation and may be positive or negative (de-modulation) dependent on whether it aids or opposes, respectively, that of the emission control electrode. This effect directly and correspondingly modifies the conversion gain of the 60 tube. Again, since the signal frequency is ordinarily below the oscillator frequency, the oscillator voltage on the adjacent electrode is of opposite polarity to that on the emission control electrode, and the signal input circuit is capacitive 65 with respect to the oscillator frequency, this voltage on the signal input grid is of opposite polarity to that of the emission control electrode or oscillator grid, and therefore produces a re-modulating effect.

70 A third effect is due to what may be termed the "space-charge coupling" between the virtual cathode and the signal input electrode. Variations in the space charge of the virtual cathode are produced primarily by the emission control electrode and, since a positive voltage on this

electrode increases the negative space charge and thus the positive charge induced upon the signal input grid, the space-charge coupling may be considered as a "negative capacitance" between the two control grids. The nature of this coupling is thus opposite to that of the capacitive coupling between the signal input electrode and the oscillator anode but, due to the fact that the oscillator grid and anode voltages are also opposite in phase, the resultant remodulating 10 effect of the space-charge coupling is similar to, and cumulative with, that of the geometric capacitive coupling described above, thus modifying the conversion gain of the tube in a similar manner.

15 Thus it is seen that, under the particular conditions described, that is, and oscillator-modulator in which the oscillator frequency is higher than the signal input frequency, all three factors described above contribute to a reduction in the 20 overall conversion gain of the system.

It is an object of my invention, therefore, to provide a signal-translating and -modulating system, including a vacuum tube of the type described above, in which the behavior of the 25 modulator and associated circuits is substantially independent of the capacitive coupling of various kinds between the several electrodes thereof.

More specifically, it is an object of my invention to provide a signal-translating and -modulating system, including a vacuum tube of the type described above, in which an external interconnection between the signal input electrode and the emission control electrode effects a transfer of current therebetween to compensate for, 25 and to neutralize the effects of, the transfer of current between these circuits by the capacitive coupling therebetween, namely, the geometrical and/or the space-charge coupling.

In accordance with my invention, a signal- 40 translating and -modulating system including a vacuum tube having a cathode, a virtual cathode, an output electrode, and control electrodes for independently controlling the electron current from the cathode and from the virtual cathode, 45 is provided with means for supplying currents to the signal input or amplification control electrode circuit and the emission control electrode circuit, the effects of which are equal and opposite to the capacitive coupling effects noted above. More 50 specifically, in accordance with my invention, the means for reducing the above-noted effects of the capacitive coupling between the electrodes comprises external capacitive couplings between the signal input or amplification control electrode 55 and between the emission control electrode and points in the system the potential variations of which are related in a proper manner in phase and magnitude to those of the electrodes which give rise to the described disturbing effects. For 60 example, the coupling may be made between the amplification control electrode and the emission control electrode adjacent the actual cathode, in case the tube is included in an oscillator-modulator system. In general, the value of this external coupling necessary to compensate for the 65 geometrical capacitive coupling, described above, may be determined from the relation that the ratio of the value of the external coupling to that of the inherent coupling between two electrodes is substantially equal to the ratio of the amplitude of the potential variations of the electrode giving rise to the disturbing effects to that of the point at which the external coupling is made. The 70 value of the external coupling necessary to com- 75

pense for the space-charge coupling may best be determined experimentally by adjusting the value of this coupling to neutralize the undesired capacitive couplings and thereby to secure normal conversion gain.

For a better understanding of my invention, together with other and further objects thereof, reference is had to the following description taken in connection with the accompanying drawing, 10 and its scope will be pointed out in the appended claims.

The single figure of the drawing is a schematic circuit diagram of a complete superheterodyne radio receiver including an oscillator-modulator 15 embodying my invention.

Referring now more particularly to the drawing, there is shown schematically a circuit diagram of a complete superheterodyne receiver modified in accordance with my invention. This receiver 20 comprises an input circuit 10 for connection between an antenna 11 and ground, connected to a radio-frequency amplifier 12, the output circuit of which is connected to a coupling transformer 13 tunable by a condenser 14. The tunable circuit 13-14 is connected to the signal input or amplification control electrode 15a of a vacuum tube 15 provided also with the usual cathode 15b of any suitable type and an anode 15c. Included in the circuit from cathode to ground is a biasing resistor 16 and a by-pass condenser 17.

The radio-frequency energy derived from the input circuit 10 may be utilized to modulate a source of local oscillations generated either in a separate tube or, as shown, in the tube 15 which is provided with additional electrodes 15d and 15e. The electrode 15e constitutes the emission control electrode or oscillator grid, while electrode 15d comprises the oscillator anode and is connected to a suitable source of direct voltage, indicated as +B, through a resistor 22. The oscillation circuit comprises a variable tuning condenser 19, and an aligning condenser 21 connected in series across an inductance 20, this circuit being connected between the oscillator grid 15e and ground. A grid leak 20a is preferably connected from the junction of inductance 20 and condenser 21 to the cathode 15b, as illustrated. A feedback from the oscillator anode circuit to the grid circuit is provided by means of an inductance 23 included in the anode circuit and coupled to the inductance 20; a condenser 24, directly coupling the lower terminals of the inductances 20 and 23; and the aligning condenser 21, which is common to the oscillator grid and anode circuits. The vacuum tube 15 is preferably provided also with a screen grid 15f interposed between the amplification control electrode 15a and the anode 15c and connected to a suitable source of direct voltage, indicated as +Screen, through a resistor 25 and a by-pass condenser 26. The tuning condensers 14 and 19 are mechanically interlocked for unicontrol, as indicated by the dash lines interconnecting them, which unicontrol may be utilized also to tune the circuits of the radio frequency amplifier 12.

The modulated carrier wave produced by the foregoing apparatus is transmitted through the tuned coupling transformer 18 to an intermediate-frequency amplifier 27, thence through a detector 28 and an audio-frequency amplifier 29 to a sound reproducing device, such as a loudspeaker 30.

The above-described apparatus constitutes a conventional superheterodyne radio receiver, as modified in accordance with the teachings of my aforementioned patent, and, per se, constitutes no

part of my present invention, so that a detailed explanation of its operation is deemed unnecessary. In brief, the signal-modulated carrier wave received from the antenna circuit 10 is amplified in the radio-frequency amplifier 12 and, thus 5 amplified, is impressed upon the control electrode 15a of the combined oscillator-modulator 15. The cathode 15b, oscillator grid 15e and anode 15d, together with their associated coupled oscillatory circuits, constitute a source of local oscillations 10 which are effective to cause a periodic fluctuation in the emission from the cathode 15b and, thus, a periodic fluctuation in the available source of electrons for the amplification modulation section 15 of the tube 15.

As described in more detail in my aforementioned patent, the oscillator anode 15d, which is of grid construction, is maintained at a positive potential by virtue of its connection to the terminal +B and attracts electrons emitted from the 20 cathode 15b which, because of their high velocity, largely pass through the mesh of the electrode 15d. The magnitude of this stream of electrons is caused to fluctuate periodically by virtue of the oscillator grid 15e. The amplification control electrode 15a, on the other hand, is maintained negative with respect to the cathode 15b by the magnitude of the biasing potential across resistor 16. This latter electrode is effective to retard the progress of the electrons beyond the oscillator 25 anode 15d, and a large portion of them is turned back toward the positively charged electrode 15d. This action results in a mass or cloud of electrons which normally exists between the electrodes 15d and 15a, which has been termed a "virtual cathode" 30 in that it has many of the characteristics of the actual cathode, although it is not actually a cathode structure.

The electron emission from the secondary or virtual cathode is controlled by the electrode 15a 40 in a manner very similar to the control by a grid electrode in an ordinary triode. The result of this arrangement is that the signal input voltage, impressed upon the control electrode 15a, is effective to modulate the locally produced oscillations 45 to produce an intermediate signal-modulated frequency which may be amplified and/or converted in any desired manner.

In a circuit arrangement of the type just described where, in general, the composite functions 50 of emission and modulation or amplification control are effected in a single tube, there is a tendency toward a modification of the apparent conversion gain of the oscillator-modulator system due to one or both of the effects of regeneration 55 and remodulation. As stated above, these effects can be traced to the inherent coupling between the amplification or modulation control electrode and the emission control electrode and/or the interposed electrode, or their connected circuits. The 60 term "inherent coupling" is employed herein to denote the interelectrode capacitance between two electrodes, for example, the electrodes 15a and 15d, as well as any residual capacitive coupling between their associated circuits. 65

In accordance with my invention, this effect on the conversion gain of the oscillator-modulator system is substantially eliminated or neutralized by an external coupling from the amplification control electrode 15a and the emission control 70 electrode 15e to sources of voltage effective to transfer currents to their respective circuits having effects equal and opposite to those resulting from the inherent capacitive coupling of these electrodes with one or more of the electrodes with- 75

in the tube. This neutralizing effect may be derived in any of a number of ways. For example, the amplification control electrode and the modulation control electrode may be connected to 5 points in the system at which the potential variations are related in phase and magnitude to those which result in the above-described effects.

Specifically, when my invention is applied to an oscillator-modulator of the type described in 10 which the potential variations of the oscillator grid 15e and anode 15d are in phase opposition, the amplification control electrode 15a and the oscillator grid 15e may be externally capacitively coupled in any suitable manner, as by a 15 condenser 31. By this means not only is there developed on the signal input or amplification control electrode a voltage of oscillation frequency effective to compensate for that developed thereon by the inherent capacitive coupling of this 20 electrode with the oscillator anode 15d and by the space-charge coupling of the virtual cathode tending to effect remodulation, but also there is developed on the emission control electrode a voltage of signal input frequency effective to compensate for that developed upon the oscillator anode 15d and, by the inherent capacitive coupling with the control electrode 15a, tending to effect 25 regeneration. Thus, regeneration and remodulation are substantially eliminated and a maximum 30 overall conversion gain of the oscillator-modulator system may be obtained.

As stated above, the value of the capacitance of the coupling condenser 31 required to neutralize that component of the capacitive coupling 35 comprising the geometrical capacitive coupling between the electrodes, is determined by the relation that the ratio of the capacitance of the condenser 31 to that of the inherent coupling between the oscillator anode 15d and the control 40 electrode 15a is substantially equal to the ratio of the amplitude of the potential variations of the electrode 15d to that of the oscillator grid 15e at which the external coupling is made. The value of the external coupling necessary to compensate 45 for the inherent space-charge coupling can be determined only experimentally under normal operating conditions, but it is generally of the order of a few micromicrofarads. The coupling condenser 24 may be adjusted to aid in neutralizing 50 this latter coupling. In a specific circuit, utilizing a pentagrid converter of the A1 type as the tube 15, a value of capacitance for the condenser 31 of from 1.0 to 1.3 micromicrofarads was found to be satisfactory.

55 While I have indicated sources of direct voltage symbolically denoted as +Screen and +B, it is to be understood that any suitable source of operating voltage for the system as a whole may be utilized, such as a conventional battery or a rectifier and filter.

60 While I have described what I at present consider the preferred embodiment of my invention, it will be obvious to those skilled in the art that various changes and modifications may be made 65 therein without departing from my invention, and I, therefore, aim in the appended claims to cover all such changes and modifications as fall within the true spirit and scope of my invention.

70 What is claimed is:

75 1. A signal-translating and -modulating system including a vacuum tube having a cathode, an output electrode, and a plurality of grid electrodes interposed therebetween, an input circuit connected to a first of said grid electrodes, a cir-

cuit of substantial impedance connected to an adjacent grid electrode nearer said cathode, whereby a voltage of input frequency developed on said latter electrode has a regenerative effect on said input circuit, and means for substantially eliminating the effect of said regenerative action on the conversion gain of the system comprising means for supplying to one of said grid electrodes a current of input frequency having an effect on the resultant electron stream to said anode 10 equal and opposite to that of said regenerative effect. 5

2. A signal-translating and -modulating system including a vacuum tube having a cathode, at least three grid electrodes and an output electrode spaced in the order named, a signal input circuit connected to the third of said grid electrodes, a circuit of substantial impedance connected to the second of said grid electrodes, whereby a voltage of input frequency developed on said second electrode has a regenerative effect on said input circuit, and means for substantially eliminating the effect of said regenerative action on the conversion gain of the system comprising means for supplying to said first grid electrode a 20 current of input frequency having an effect on the resultant electron stream equal and opposite to that of said regenerative effect. 15

3. A signal-translating and -modulating system including a vacuum tube having a cathode, an output electrode, and a plurality of grid electrodes interposed therebetween, an input circuit connected to a first of said grid electrodes, a circuit of substantial impedance connected to an adjacent grid electrode nearer said cathode, whereby a 30 voltage of input frequency developed on said latter electrode has a regenerative effect on said input circuit, and means for substantially eliminating the effect of said regenerative action on the conversion gain of the system comprising an 40 external capacitive coupling from one of said grid electrodes to a point in said system the potential variations of which are related in phase and magnitude to those developed on said second-named electrode. 35

4. A signal-translating and -modulating system including a vacuum tube having a cathode, an output electrode, and a plurality of grid electrodes interposed therebetween, a signal input circuit connected to a first of said grid electrodes, a circuit including a source of oscillations and having a connection to at least one of the other of said grid electrodes, an inherent capacitive coupling between said input electrode and said other grid electrode, whereby a voltage of oscillation frequency developed on said signal input electrode has a remodulating effect on the output of said tube, and means for substantially eliminating the effect of said remodulating action on the conversion gain of the system comprising means for supplying to one of said grid electrodes a current of oscillation frequency having an effect on the resultant electron stream to said anode equal and opposite to that of said remodulating effect. 55

5. A signal-translating and -modulating system including a vacuum tube having a cathode, at least three grid electrodes and an output electrode spaced in the order named, a signal input circuit connected to the third of said grid electrodes, an oscillation system including connections to said first and second grid electrodes, an inherent capacitive coupling between said signal input electrode and said oscillation system and its associated electrodes, whereby a voltage of oscillation frequency developed on said signal input 70 75

- electrode has a remodulating effect on the output of said tube, and means for substantially eliminating the effect of said remodulating action on the conversion gain of the system comprising 5 means for supplying to one of said grid electrodes a current of oscillation frequency having an effect on the resultant electron stream to said anode equal and opposite to that of said remodulating effect.
- 10 6. A signal-translating and -modulating system including a vacuum tube having a cathode, an output electrode, and a plurality of grid electrodes interposed therebetween, a signal input circuit connected to a first of said grid electrodes, a circuit including a source of oscillations and having a connection to at least one of the other of said grid electrodes, an inherent capacitive coupling between said input electrode and said other grid electrode, whereby a voltage of 15 oscillation frequency developed on said signal input electrode has a remodulating effect on the output of said tube, and means for substantially eliminating the effect of said remodulating action on the conversion gain of the system comprising 20 25 an external capacitive coupling from said signal input electrode to a point in said system the potential variations of which are related in phase and magnitude to those developed on said signal input electrode by said capacitive coupling.
- 30 7. A signal-translating and -modulating system including a vacuum tube having a cathode, a first control electrode, a second control electrode and an output electrode spaced in the order named, said tube having means including a third electrode interposed between said control electrodes for forming a virtual cathode therebetween, a signal input circuit connected to one of said control electrodes, an emission control circuit connected to the other control electrode, said 35 40 control electrodes having an inherent space-charge coupling therebetween, whereby a voltage of emission control frequency developed on said signal input electrode has a remodulating effect on the output of said tube, and means for substantially eliminating the effect of said remodulating action on the conversion gain of the system comprising means for supplying to one of said electrodes a current of emission control frequency having an effect on the resultant electron stream to said anode equal and opposite to that of said remodulating effect.
- 45 8. A signal-translating and -modulating system including a vacuum tube having a cathode, a first control electrode, a second control electrode and an output electrode spaced in the order named, said tube having means including a third electrode interposed between said control electrodes for forming a virtual cathode therebetween, a signal input circuit connected to one 50 55 of said control electrodes, an emission control circuit connected to the other control electrode, said control electrodes having an inherent space-charge coupling therebetween whereby a voltage of emission control frequency developed on said signal input electrode has a remodulating effect on the output of said tube, and means for substantially eliminating the effect of said remodulating action on the conversion gain of the system comprising an external capacitive coupling from said signal input electrode to a point in said system the potential variations of which are related in phase and magnitude to those developed upon said signal input electrode by said space-charge coupling.
- 60 75 9. A signal-translating and -modulating sys- tem including a vacuum tube having a cathode, a first control electrode, a second control electrode and an output electrode spaced in the order named, said tube having means including a third electrode interposed between said control electrodes for forming a virtual cathode therebetween, said control electrodes having an inherent space-charge coupling therebetween and being effective to control the electron stream from said cathode and said virtual cathode, respectively, and a condenser connected between said control electrodes effective to neutralize said space-charge coupling. 5
- 10 10. A signal-translating and -modulating system including a vacuum tube having a cathode, a first control electrode, a second control electrode and an output electrode spaced in the order named, said tube having means including a third electrode interposed between said control electrodes for forming a virtual cathode therebetween, a signal input circuit connected to one of said control electrodes, a circuit including a source of oscillations having a connection to the other of said control electrodes, whereby the space-charge coupling between said control electrodes develops a voltage of oscillation frequency upon said signal input electrode having a remodulating effect on the output of said tube, and means for substantially eliminating the effect of said remodulating action on the conversion gain of the system comprising means for supplying to said signal input electrode a current of oscillation frequency having an effect on the resultant electron stream to said anode equal and opposite to that of said remodulating effect. 15 20 25 30 35 40 45 50 55 60 65 70 75 80 85 90 95 100
11. A signal-translating and -modulating system including a vacuum tube having a cathode, a first control electrode, a second control electrode and an output electrode spaced in the order named, said tube having means including a third electrode interposed between said control electrodes for forming a virtual cathode therebetween, said control electrodes being effective to control the electron stream from said cathode and said virtual cathode, respectively, an oscillation circuit including connections to one of said control electrodes and said third electrode, and means for substantially eliminating the effect of the capacitive coupling between the other of said control electrodes and said oscillation circuit and its associated electrodes comprising a neutralizing condenser connected between said control electrodes. 45 50 55 60 65 70 75 80 85 90 95 100
12. A signal-translating and -modulating system including a vacuum tube having a cathode, a first control electrode, a second control electrode and an output electrode spaced in the order named, said tube having means including a third electrode interposed between said control electrodes for forming a virtual cathode therebetween, a signal input circuit connected to one of said control electrodes, an oscillation circuit including connections to the other of said control electrodes and to said third electrode, an inherent capacitive coupling between said input electrode and said third electrode, whereby a voltage of oscillation frequency developed on said signal input electrode has a remodulating effect on the output of said tube, said control electrodes having an inherent space-charge coupling therebetween, whereby an additional voltage of oscillation frequency developed on said signal input electrode has an additional remodulating effect, and means for substantially eliminating the effect of said remodulating effect. 55 60 65 70 75 80 85 90 95 100

- tions on the conversion gain of the system comprising means for supplying to one or more of said electrodes a current of oscillation frequency having an effect on the resultant electron stream to said anode equal and opposite to that of said remodulating effects.
13. A signal-translating and modulating system including a vacuum tube having a cathode, an output electrode, and a plurality of grid electrodes interposed therebetween, an input circuit connected to a first of said grid electrodes, a circuit of substantial impedance connected to an adjacent grid electrode nearer said cathode, whereby a voltage of input frequency developed on said latter electrode has a regenerative effect on said input circuit, a circuit including a source of oscillations and having a connection to at least one of said grid electrodes other than said input electrode, an inherent capacitive coupling between said input electrode and said last-mentioned electrode whereby a voltage of oscillation frequency developed on said signal input electrode has a remodulating effect on the output of said tube, and means for substantially eliminating the effect on the conversion gain of the system of said regenerative and remodulating actions comprising means for supplying to one of said grid electrodes a current of input frequency having an effect on the resultant electron stream to said anode equal and opposite to that of said regenerative effect and means for supplying to one of said grid electrodes a current of oscillation frequency having an effect on said resultant electron stream equal and opposite to that of said remodulating effect.
14. A signal-translating and -modulating system including a vacuum tube having a cathode, a first control electrode, a second control electrode and an output electrode spaced in the order named, said tube having means including a third electrode interposed between said control electrodes for forming a virtual cathode therebetween, a signal input circuit connected to one of said control electrodes, an oscillation circuit including connections to the other of said control electrodes, a circuit of substantial impedance connected to said third electrode, an inherent capacitive coupling between said input electrode and said third electrode whereby a voltage of input frequency developed on said latter electrode has a regenerative effect on said input circuit and whereby a voltage of oscillation frequency developed on said signal input electrode has a remodulating effect on the output of said tube, said control electrodes having an inherent space-charge coupling therebetween whereby an additional voltage of oscillation frequency developed on said signal input electrode has an additional remodulating effect, and means for substantially eliminating the effect of said regenerative and remodulating actions on the conversion gain of the system comprising means for supplying to said signal input circuit a current of oscillation frequency equal and opposite to the currents induced therein by said couplings and for supplying a current of signal input frequency to one of said electrodes having an effect on the resultant electron stream to said anode equal and opposite to that of said regenerative effect.
15. A signal-translating and -modulating system including a vacuum tube having a cathode, a first control electrode, a second control electrode and an output electrode spaced in the order named, said tube having means including a third electrode interposed between said control elec-
- trodes for forming a virtual cathode therebetween, a signal input circuit connected to one of said control electrodes, an oscillation circuit including connections to the other of said control electrodes, a circuit of substantial impedance connected to said third electrode, an inherent capacitive coupling between said input electrode and said third electrode whereby a voltage of input frequency developed on said latter electrode has a regenerative effect on said input circuit and whereby a voltage of oscillation frequency developed on said signal input electrode has a remodulating effect on the output of said tube, said control electrodes having an inherent space-charge coupling therebetween whereby an additional voltage of oscillation frequency developed on said signal input electrode has an additional remodulating effect, and means for substantially eliminating the effect of said regenerative and remodulating actions on the conversion gain of the system comprising an external capacitive coupling between said control electrodes. 5
16. A signal-translating and -modulating system including a vacuum tube having a cathode, a first control electrode, a second control electrode and an output electrode spaced in the order named, said tube having means including a third electrode interposed between said control electrodes for forming a virtual cathode between said control electrodes, a signal input circuit connected to said second control electrode, an oscillation system including connections to said first control electrode and to said interposed electrode, and means for substantially eliminating the effect on the conversion gain of the system of the inherent coupling between said signal input electrode and said oscillation system and associated electrodes comprising a coupling between said control electrodes. 10
17. A signal-translating and -modulating system including a vacuum tube having a cathode, a first control electrode, a second control electrode and an output electrode spaced in the order named, said tube having means including a third electrode interposed between said control electrodes for forming a virtual cathode between said control electrodes, a signal input circuit connected to one of said control electrodes, an oscillation system including connections to said first control electrode and to said interposed electrode, said oscillation circuit operating at a frequency substantially higher than said signal input circuit, and means for substantially eliminating negative regeneration due to the inherent coupling between said signal input electrode and said oscillation system and associated electrodes comprising a coupling between said control electrodes. 15
18. A signal-translating and -modulating system including a vacuum tube having a cathode, a first control electrode, an auxiliary electrode, a second control electrode, a screen electrode, and an output electrode spaced in the order named, said auxiliary electrode and said control electrode remote from said cathode together forming a virtual cathode, a signal input circuit connected to one of said control electrodes, an oscillation circuit including connections to the other of said control electrodes and to said auxiliary electrode, a circuit including a source of voltage for maintaining said screen electrode positive with respect to said cathode, and means for substantially eliminating the effect on the conversion gain of the system of the inherent coupling between said signal input electrode and said oscillation circuit 20

- and associated electrodes comprising an external capacitive coupling between said control electrodes.
19. A signal-translating and -modulating system including a vacuum tube having a cathode, a first control electrode, a second control electrode and an output electrode spaced in the order named, said tube having means including a third electrode interposed between said control electrodes for forming a virtual cathode between said control electrodes, a signal input circuit connected to one of said control electrodes, an oscillation system including coupled circuits one connected between said cathode and said first control electrode and the other between said cathode and said interposed electrode, and means for substantially eliminating the effect on the conversion gain of the system of the inherent coupling between said signal input electrode and said oscillation system and associated electrodes comprising a capacitive coupling between said control electrodes and a second capacitive coupling between the coupled circuits of said oscillatory system.
20. A superheterodyne radio receiver comprising means for selecting and amplifying a signal-modulated carrier wave, an oscillator-modulator for converting said carrier wave into one of lower frequency comprising a vacuum tube having a cathode, a first control electrode, an auxiliary electrode, a second control electrode and an output electrode spaced in the order named, said auxiliary electrode and said second control electrode cooperating to form a virtual cathode, a circuit coupling the output section of said amplifying means to a first of said control electrodes, an oscillation circuit including connections to the other of said control electrodes and to said auxiliary electrode, means for substantially eliminating the effect on the conversion gain of the receiver of the inherent coupling between said first control electrode and said oscillation circuit and associated electrodes comprising an external coupling between said control electrodes, means coupled to the output electrode of said oscillator-modulator for amplifying the output modulation frequency thereof, means for detecting said amplified modulation frequency, and a signal-reproducing device coupled to said detecting means.
21. In a superheterodyne radio receiver, a frequency-changing modulator arrangement comprising a vacuum tube having a cathode, a first control electrode, a screen electrode, a second control electrode, and an output electrode spaced in the order named, means for maintaining said screen electrode positive and said second control electrode negative relative to said cathode and thereby forming a virtual cathode between screen electrode and outer control electrode, a signal-frequency tuned input circuit connected between said second control electrode and said cathode, an oscillation-producing circuit connected between said first control electrode and said cathode, and a capacitance element connected between said control electrodes and proportioned substantially to neutralize at the oscillation frequency the space-charge coupling from said first control electrode to said second control electrode caused by said virtual cathode.
